Primary Examiner — Marissa J Cash*Assistant Examiner* — Pravin Giri(74) *Attorney, Agent, or Firm* — Elevated IP, LLC(57) **CLAIM**

The ornamental design for a wheel chock, as shown and described.

DESCRIPTION

FIG. 1 is a top perspective view of an ornamental design for a wheel chock;

FIG. 2 is a front plan view thereof;

FIG. 3 is a back plan view thereof;

FIG. 4 is a right side view thereof;

FIG. 5 is a left side view thereof;

FIG. 6 is a top plan view thereof; and,

FIG. 7 is a bottom plan view thereof.

The broken lines are for purposes of illustrating environmental structure and form no part of the claimed design.
